ABSTRACT OF THE DISCLOSURE

A flat paint brush carried by a sleeve slidably mounted on an elongated handle. A guide plate is situated closely adjacent the side face of the flat brush and is pivotal for turning movement relative to the carrier sleeve about an axis perpendicular to the plane of the guide plate. A spring yieldably maintains the plate in a rest position wherein its guide edge extends perpendicularly to the handle, and returns it to the rest position after the plate has been turned. A second spring in the hollow handle acts on the carrier sleeve for displacing it with respect to the handle to a rest position wherein the guide plate extends beyond the paint-applying end of the flat brush.

The present invention relates to painting.

More particularly, the present invention relates to painting, by means of a paint brush, areas which terminate in sharply defined edges.

In carrying out various painting jobs, numerous objects are encountered, such as, for example, in the case of painting window frames, where it is necessary to paint an area which terminates in a sharply defined edge. In the case of a window frame, for example, it is conventional to paint the frame with the pane of glass carried thereby, so that an area which terminates in a sharply defined edge at the boundary between the frame and the glass must be painted. In general, it is conventional to paint such areas in a freehand manner with a suitable paint brush. Inasmuch as it is impossible to avoid certain irregularities in the painted areas under these conditions, it is in most cases essential to carry out subsequent operations, after the painting has been carried out, so that, for example, the excess paint applied to the glass pane must be wiped or scraped off. The same considerations apply to other types of painting work, such as for example, when painting up to the edges of differently colored wall areas.

In order to maintain the subsequent wiping or scraping operations, which are relatively expensive, at a minimum, it is known when painting the edges of a given area to apply, by hand, to the area which is not to be painted a device such as a suitable spatula which is progressively held along the edge so as to cover the portion not to be painted while defining the edge of the area which is to be painted. When working in this manner, it is necessary to take into consideration the disadvantage of requiring the spatula to be frequently cleaned after painting of relatively short distances, so that the painting operations are considerably delayed with this type of protection for the unpainted area. It is also known to provide sharply defined edges for painted areas by applying along the border of the area which is to be painted suitably masking in the form of paper or self-adhesive strips, made either of paper or plastic sheet material or the like. In this case, however, the cost of the masking material must be taken into consideration, quite aside from the fact that additional costs are involved simply in the labor required to apply and remove the masking material.

2

Thus, these known operating methods are in part unsatisfactory and in part tied up with considerable expense, both with respect to time and cost, so that there is a need for a device which without any particular cost, either in time or money, makes it possible to paint areas which terminate in sharply defined edges.

It is, therefore, a primary object of the present invention to fill this latter need.

Thus, it is an object of the invention to provide a relatively simple device which will enable a paint brush to be manipulated in such a way that it will produce a sharply defined edge for a painted area.

Furthermore, it is an object of the present invention to provide a device of this type which makes it quite simple to load the paint brush with a supply of paint.

In addition, it is an object of the present invention to provide a device which, while reliably preventing the paint brush from having access to an undesired area, will at the same time permit the paint brush to apply paint freely to the area which is required to be painted all the way up to a predetermined edge.

Moreover, it is an object of the invention to provide a device of this type which enables the paint brush to be tilted in any desired direction while maintaining the sharply defined edge for the painted area.

Furthermore, it is an object of the present invention to provide a device of this type which enables restricted areas, such as corners, to be very easily painted.

The objects of the present invention also include a device of this type which permits the brush to be very easily manipulated not only during the painting operations but also during loading of the brush with a fresh supply of paint, in such a way that, for example, only one hand of the operator is required for the operations so that the other hand of the operator is free for other purposes.

Also, the objects of the invention include the provision of a device of this type which enables not only the paint brush but also a guide therefor to be easily replaced so that the paint brush and the guide can be separated from the device for easy cleaning as well as for exchanging with other guides and paint brushes as, for example, when changing from one paint color to another paint color.

Among the objects of the present invention is also included the provision of a device which can be very easily protected against becoming itself undesirably covered with paint.

Also, it is an object of the invention to provide a device of the above type which can be manufactured from readily available material, such as any suitable metals or plastics.

In accordance with the invention, the device includes a relatively flat paint brush having a substantially flat side face and terminating in a free, paint-applying end portion where the bristles of the brush are situated. An elongated hollow handle means is connected with the paint brush so as to carry the latter, and a carrier means is supported by the handle means for longitudinal shifting movement with respect thereto. A guide plate is situated in a plane parallel to the substantially flat side face of the paint brush, closely adjacent to the latter side face in the region of the free end portion of the paint brush where the bristles thereof are located, and the area of this guide plate is greater than that of the free end portion of the paint brush, the guide plate terminating in an elongated guide edge. A pivot means mounts the guide plate on the carrier means for pivotal movement with respect thereto about an axis which extends perpendicularly with respect to the plane in which the guide plate is located, and a first spring means is operatively connected to the guide plate to yieldably maintain the latter in a predetermined rest position where its guide edge extends perpendicularly with re-

spect to the elongated handle means, so that when the guide plate is tilted from its rest position it will automatically be returned back to this rest position by this first spring means. A second spring means is situated within the elongated hollow handle means and acts on the carrier means to urge the latter to a predetermined rest position where the guide plate extends in all directions outwardly beyond the free, paint-applying end portion of the paint brush.

The invention is illustrated by way of example in the accompanying drawings which form part of this application and in which:

FIG. 1 shows one possible embodiment of a device according to the present invention, in a partly sectional side elevation;

FIG. 2 shows in elevation a guide-plate holder, together with a guide plate, after this subassembly has been removed from the remainder of the device; and

FIG. 3 shows in elevation the paint brush itself after it has been removed from the rest of the assembly.

Referring now to FIG. 1, the device of the invention, which is illustrated therein, includes an elongated hollow handle means 1 which has a lower closed end 2. This elongated hollow handle means 1 is in the form of an elongated metal or plastic tube which is provided with its bottom closed end 2 either by swaging, or by simply clamping together and soldering the wall portions of the hollow tube 1 at the region of its bottom end. The bottom end may be welded, for example, so as to become closed in the manner shown in the lower part of FIG. 1. While the elongated hollow handle means 1 can have a cross section of any configuration, in the illustrated example it has a simple circular cross section.

A carrier means is mounted on the elongated handle means 1 for longitudinal shifting movement with respect thereto, and this carrier means includes an elongated sleeve 3 through which the elongated handle means 1 slidably extends. A spring means is situated in the interior of the elongated hollow handle means 1 to urge the carrier means to the illustrated rest position where the sleeve 3 is in the region of the upper end of the handle 1, as viewed in FIG. 1. In the illustrated example, this spring means takes the form of an elongated coil spring 4 which is under compression within the hollow interior of the handle 1, the bottom end of the spring 4 engaging the closed lower end 2 of the handle 1 while the upper end of the spring 4 engages a cross pin 5 which is carried by the sleeve 3 in the region of the lower end thereof.

This cross pin 5 forms part of the carrier means and is situated at its opposite ends in a pair of aligned openings formed in the sleeve 3. In order to guide the sleeve 3 and the cross pin 5, this cross pin extends through a pair of longitudinally extending slots 6 which are formed in the elongated hollow handle 1, these slots 6 being coextensive and situated at diametrically opposed parts of the tube 1, so that in this way the cross pin 5 extends through the slots 6 into the openings of the sleeve 3 which carry the cross pin 5. Thus, the spring 4, due to its compression, will urge the sleeve 3 to the position illustrated in FIG. 1 where the pin 5 engages the upper ends of the slots 6, and in this way the rest position of the carrier means is determined. The slots 6 each have a length which is approximately the same as the length of the sleeve 3, and the lower ends of the slots 6 cooperate with the pin 5 to limit the extent of shifting movement of the carrier means with respect to the handle means 1.

A protective member 7 is carried by the handle means 1 for protecting the sleeve 3 against paint, and for this purpose the protective member is fixed at its bottom end to the handle 1, as by being welded thereto. This protective member 7 takes the form of an elongated tubular member having an upper open end surrounding the handle 1 and forming with the latter an annular gap through which the sleeve 3 can freely pass into the interior of the protective member 7. This protective member 7 is

situated in the region of the handle means 1 along which the sleeve 3 shifts, so as to protect the latter.

A relatively flat paint brush 8 is inserted into the upper open end of the elongated handle means 1, which thus becomes connected to the paint brush 8 so as to form a handle for the latter. The bristles of the paint brush 8 form for the latter a free, paint-applying end portion, and this paint brush 8 has a substantially flat side face, as is particularly apparent from FIGS. 1 and 3. The paint brush includes a flat holder 9 which carries the bristles of the brush, and this holder 9 is connected to one end of an elongated channel member 10 which is received in the upper open end portion of the elongated handle 1. This elongated channel member 10, which is fixed to and extends from the flat holder 9 of the brush bristles, has at least two pairs of curved projections 11 extending from opposed side edges of the channel member 10 so as to form with the latter a pair of tubular portions which are capable of sliding into and frictionally engaging the inner surface of the handle 1 with a force of friction sufficient to retain the brush in the position illustrated in FIG. 1 while at the same time permitting the ready removal of the brush whenever desired. The exterior surface of the channel member 10 together with the projections 11, at 15 the tubular portions where the projections 11 are located, has a diameter equal to the inner diameter of the tube 1. Therefore, at any time the brush can be pushed into the handle 1 so as to be reliably held thereby, while at the same time permitting the brush to be separated from the handle 1 whenever desired.

The device further includes an exchangeable, flat guide plate 12 which is carried by the carrier means, this carrier means including sleeve 3 and the cross pin 5, as pointed out above. The carrier means further includes a 20 holder 13 which carries a pivot means which pivotally supports the guide plate 12. This guide plate 12 has an approximately semi-circular configuration, as is apparent from FIG. 2, although instead of taking the configuration of a half-circle, it may also take the configuration of half-oval. The pivot means which supports the plate 12 on the carrier means is formed by a simple pivot pin 14 which 25 turnably carries the guide plate 12 and which is itself fixedly carried by the holder 13, which forms part of the carrier means of the invention.

As is apparent from FIG. 1, the guide plate 12 is situated in a plane which is parallel to the plane of the substantially flat side face of the brush 8, closely adjacent to this latter plane. Furthermore, the guide plate 12 has a straight guide edge 21 and in addition has an area which 30 is substantially greater than the free, paint-applying end portion of the brush 8. Thus, the pivot means 14 supports the guide plate 12 for turning movement about an axis which is perpendicular to the plane in which the guide plate 12 is located as well as the plane in which the substantially flat side face of the brush is located.

A spring means 15 is operatively connected with the guide plate 12 so as to maintain the latter yieldably in a predetermined rest position, and in this rest position the guide edge 21 extends perpendicularly with respect to the 35 elongated handle means 1. The spring means always seeks to return the guide plate 12 to an intermediate rest position from which the guide plate 12 can be turned, by way of the pivot means 14, in either direction. The holder 13 of the carrier means carries the spring means 15 which 40 takes the form of an elongated coil spring which is under tension and which is connected at one end to the plate 12. In the rest position of the guide plate 12, to which it is urged by the spring means 15, this guide plate extends in 45 all directions outwardly beyond the free, paint-applying end portion of the brush 8.

The holder 13 of the carrier means is in the form of a one-piece member having a plate portion 16 to which the pivot pin 14 is fixedly connected, and this plate portion 16 extends from a side edge of a substantially trough-

shaped portion 17 of the holder 13, the spring 15 being situated within the trough-shaped portion 17.

As pointed out above, the spring 15 is connected at one end to the guide plate 12, and the other end of the spring 15 is connected to a side of the trough-shaped portion 17 which is distant from the plate portion 16 of the holder 13. The side of the trough-shaped portion 17 to which the spring 15 is connected is also connected with a pair of curved claws 18 which extend around and frictionally engage the sleeve 3 of the carrier means so as to form part of the carrier means therewith. In this case also, the frictional engagement of the claw members 18 with the sleeve 13 is sufficient to retain the parts reliably in the assembled condition shown in FIG. 1, while at the same time permitting the holder 13 to be removed so as to form a unit separate from the rest of the assembly, as indicated in FIG. 2.

The holder 13 is provided with a laterally extending actuating lug 19, this lug extending rearwardly away from the brush, for example, and by engaging the actuating lug 19 it is a simple matter to move the holder 13 as well as to support it at the edge of a paint can when it is desired to dip the brush into the paint, for example. In order to protect the spring 15 it is loosely surrounded by a protective tube 20 made, for example, of a suitable plastic, so that in this way the spring 15 will not become soiled.

It is possible to shift the entire carrier means 3, 13 in opposition to the spring 4 to such an extent that the guide plate 12 is situated beyond the region of the free end portion of the brush 8, so that, for example, the guide edge 21 becomes situated at the region of the holder 9 which carries the bristles of the brush. With the parts in this position it is a simple matter to dip the brush bristles into the paint. The same results can be achieved when the actuating lug 19 is placed against the edge of a paint container, and with the parts directed downwardly, which is to say in a position inverted from that shown in FIG. 1, the handle 1 is pushed down, so that in this way the brush is lowered beyond the edge 21 to dip into the paint, assuming that there is sufficient paint in the container for this purpose.

In order to use the device of the invention, the guide edge of the guide plate 12 is placed along the boundary edge between the area which is to be painted and the area which is not to be painted, and at the same time the brush 8 is pressed against the area which is to be painted. During this operation the guide plate 12 is pressed back in opposition to the spring 4 to an extent sufficient to place the bristles of the brush 8 in engagement with the surface which is to be painted so as to apply paint thereto.

The device of the invention can be made of any suitable, relatively rigid sheet material, such as metal and/or plastic. This applies particularly to the handle 1, the protective member 7, the carrier means formed by the sleeve 3 and the holder 13 for the guide plate 12, and of course for the guide plate 12 itself.

Because of the pivotal mounting provided by way of the pivotal means 14 for the guide plate 21, it is possible for the operator to tilt the brush 8 while applying the latter to the area which is to be painted. In order to bring the brush into engagement with the area which is to be painted, it is only necessary to push on the handle 1 in opposition to the spring 4. The guide plate 12 will of course prevent the brush from having access to that area which is not to be painted. It is only necessary to hold the edge 21 along the boundary between the areas which are to be painted and which are not to be painted. Under these conditions it is possible for the operator to tilt the brush in any required direction as a result of the pivotal mounting derived by way of the pivotal means 14. Thus, the brush can be actuated in a conventional manner.

As a result of the substantially semi-circular or half-oval configuration of the guide plate 12 it is possible to provide, in an extremely convenient, faultless manner, sharply defined edges for an area which is to be painted in

the region of a corner where operations of this type would normally be relatively difficult to carry out.

The actuating lug 19 of course greatly facilitates loading the brush with a fresh supply of paint, as pointed out above. It is to be noted in this connection that the operator need only apply the lug 19 at an edge of the paint can and depress the handle 1, so that only one hand is required for this purpose, thus freeing the other hand of the operator for other operations.

As was pointed out above, not only the brush but also the holder 13 are easily removable from the assembly so that it is a simple matter to clean both of these units as well as to exchange them for other units, as when changing over from one paint color to another paint color.

The protective member 7 will of course protect the handle 1 from being covered with paint, particularly at the area along which the sleeve 3 of the carrier means slides. In the same way the protective member 20 protects the spring 15. The members 7 and 20 may be made of sheet metal or plastic.

When the holder 13 is removed, so as to have the condition shown in FIG. 2, it is a simple matter to clean the plate 12 or to replace the entire unit shown in FIG. 2 with another unit. Also, when the brush 8 is removed, so as to have the condition shown in FIG. 3, the brush can be easily cleaned and replaced by another brush having the construction shown in FIG. 3.

What is claimed is:

1. A device for painting areas which terminate in sharply defined edges, comprising a relatively flat paint brush having a substantially flat side face and having a paint-applying free end portion, elongated hollow handle means connected with and extending from said paint brush so as to support the latter, carrier means including an elongated sleeve supported by said elongated handle means for longitudinal sliding movement along said handle means and carrying a cross pin which extends through, and is carried by, said sleeve, said elongated hollow handle means being formed with longitudinal slots through which said cross pin extends, a guide plate situated closely adjacent to but spaced from said substantially flat side face of said brush in a plane parallel to said side face, said guide plate terminating in a free elongated guide edge situated in the region of said free end portion of said brush, and said guide plate having an area greater than that of said side face of said brush, pivot means connecting said guide plate to said carrier means for turning movement relative thereto about an axis perpendicular to said plane in which said guide plate is situated, first spring means operatively connected with said plate for yieldably maintaining the latter in a rest position where said guide edge thereof extends perpendicularly with respect to said elongated handle means, said first spring means, after said plate is turned with respect to said carrier means from said rest position, automatically returning said guide plate to said rest position, and second spring means including an elongated spring situated in said elongated hollow handle means and said cross pin engaging one end of said elongated spring in the interior of said elongated handle means, said slots of said handle means terminating in ends which cooperate with said cross pin to limit the movement of said sleeve of said carrier means with respect to said elongated hollow handle means to act on said carrier means for displacing the latter with respect to said handle means to a rest position where said guide plate extends in all directions beyond said free paint-applying end portion of said brush.
2. A device as recited in claim 1 and wherein said brush includes a flat bristle holder and an elongated channel member fixed at one end to said holder and extending from the latter into the interior of said handle means, said channel member having at least two pairs of lugs extending from opposed side edges of said channel member and forming with said channel member a pair of tubular por-

tions received in and engaging said elongated hollow handle means for connecting said brush thereto.

3. A device as recited in claim 1 and wherein said carrier means includes an elongated sleeve through which said hollow handle means slidably extends so that said sleeve is shiftable along said handle means, and a holder carrying said pivot means so as to support said guide plate, said holder being carried by and extending from said sleeve and having a laterally projecting actuating lug which may be acted upon to provide movement of said carrier means and handle means, one with respect to the other.

4. A device as recited in claim 3 and wherein said holder of said carrier means is made of a one-piece member having a plate portion carrying said pivot means and an elongated trough-shaped portion terminating in a side edge from which the said plate portion of said holder extends, said first spring means being situated in said trough-shaped portion and being in the form of an elongated tension spring connected at one end to said guide plate and at an opposite end to a side of said trough-shaped portion distant from said plate portion of said holder of said carrier means, said holder having curved claw members extending at least part way around and engaging said sleeve for connecting said holder thereto.

5. A device as recited in claim 4 and wherein a protective tube loosely surrounds said first spring means.

6. A device as recited in claim 1 and wherein said guide plate has an approximately semi-circular configuration.

7. A device as recited in claim 1 and wherein said carrier means includes an elongated sleeve surrounding said elongated handle means and longitudinally shiftable along said handle means, and an outer protective member carried by said handle means in that region thereof along which said sleeve is shiftable, said sleeve being situated between said protective member and said handle means so as to be protected by said protective member.

8. A device as recited in claim 7 and wherein said elongated handle means, said protective member carried thereby, said carrier means, and said guide plate are all made of a substantially rigid sheet material.
